[57] CLAIM

The ornamental design for a shoe upper, as shown and described.

DESCRIPTION

FIG. 1 is a side elevational view of one side of a shoe upper showing my new design;
FIG. 2 is a side elevational view of the other side of the shoe upper shown in FIG. 1;
FIG. 3 is a top plan view of the shoe upper shown in FIG. 1;
FIG. 4 is a front elevational view of the shoe upper shown in FIG. 1; and,
FIG. 5 is a rear elevational view of the shoe upper shown in FIG. 1.
The broken line showing of a shoe sole is for illustrative purposes and forms no part of the claimed design.

FIG. 1

FIG. 3

FIG. 4

FIG. 5
